UNITED STATES PATENT OFFICE

167,362

GRATER

Valeriano I. Morante, San Francisco, Calif.

Application September 1, 1951, Serial No. 16,491

Term of patent 14 years

(Cl. D89—1)

To all whom it may concern:

Be it known that I, Valeriano I. Morante, a citizen of the Philippine Republic, residing at San Francisco, in the county of San Francisco and State of California, have invented a new, original, and ornamental Design for a Grater, of which the following is a specification, reference being had to the accompanying drawing, forming part thereof.

I claim:

The ornamental design for a grater, substantially as shown.

VALERIANO I. MORANTE.
